DESCRIPTION

FIG. 1 is a perspective view from below of a combination ceiling fan and light fixture in accordance with our design; FIG. 2 is a top plan view of the combination ceiling fan and light fixture in accordance with our design;

FIG. 3 is a bottom plan view of the combination ceiling fan and light fixture in accordance with our design;

FIG. 4 is a side elevation view of the combination ceiling fan and light fixture in accordance with our design, the opposite side being a mirror image of that shown; and,

FIG. 5 is a front perspective view from below of the combination ceiling fan and light fixture in accordance with our design.

The broken line showing of the support pole is included for the purpose of illustrating environmental structure and forms no part of the claimed design.
